CLAIM

What is claimed is the ornamental design for a billet push rod, as shown and described.

DESCRIPTION

FIG. 1 is a top view of the rod;

FIG. 2 is a bottom view of the rod;

FIG. 3 is a front view of the rod;

FIG. 4 is a rear view of the rod;

FIG. 5 is a left-end view of the rod;

FIG. 6 is a right-end view of the rod;

FIG. 7 is a perspective view of the rod; and,

FIG. 8 is an alternate perspective view of the rod.

The broken lines in the drawings depict unclaimed environmental subject matter.
